US00D905269S

(12) **United States Design Patent** (10) Patent No.: **US D905,269 S**
(45) Date of Patent: **** Dec. 15, 2020**

(54)	SINGLE PIECE REAGENT HOLDER	4,018,652 A	4/1977	Lanham et al.
(71)	Applicant: BECTON, DICKINSON AND COMPANY , Franklin Lakes, NJ (US)	4,038,192 A	7/1977	Serur
(72)	Inventors: Ammon David Lentz , York, PA (US); Richard St. Pierre , Québec (CA); Dwight Livingston , Fallston, MD (US); Adam Bruce Steel , Fallston, MD (US)	4,055,395 A	10/1977	Honkawa et al.
(73)	Assignee: Becton, Dickinson and Company , Franklin Lakes, NJ (US)	D249,706 S	9/1978	Adamski
(**)	Term: 15 Years	4,139,005 A	2/1979	Dickey
(21)	Appl. No.: 29/667,419	D252,157 S	6/1979	Kronish et al.
(22)	Filed: Oct. 22, 2018	D252,341 S	7/1979	Thomas
	Related U.S. Application Data	D254,687 S	4/1980	Fadler et al.
(62)	Division of application No. 29/540,566, filed on Sep. 25, 2015, now Pat. No. Des. 831,843, which is a division of application No. 29/470,378, filed on Oct. 21, 2013, now Pat. No. Des. 742,027, which is a division of application No. 29/403,131, filed on Sep. 30, 2011, now Pat. No. Des. 692,162.	4,212,744 A	7/1980	Oota
(51)	LOC (12) Cl. 24-01	D261,033 S	9/1981	Armbruster
(52)	U.S. Cl.	D261,173 S	10/1981	Armbruster
	USPC D24/224	4,301,412 A	11/1981	Hill et al.
(58)	Field of Classification Search	4,439,526 A	3/1984	Columbus
	USPC D24/107, 186, 216, 219, 220, 221, D24/223-227, 231, 232; D10/81	4,457,329 A	7/1984	Werley et al.

(57) CLAIM

The ornamental design for a single piece reagent holder, substantially as shown and described.

DESCRIPTION

FIG. 1 is a perspective view of a single piece reagent holder showing an embodiment of the new design; FIG. 2 is a first side view thereof; FIG. 3 is a second side view thereof; FIG. 4 is a top plan view thereof; FIG. 5 is a bottom plan view thereof; FIG. 6 is a first end view thereof; and, FIG. 7 is a second end view thereof.

The broken lines in the drawing views are included for the purpose of illustrating portions of the single piece reagent holder that form no part of the claimed design.
